6 Claims. (Cl. 315—39)

This invention relates to electronic valves having an electrode structure producing a current of stably bunched electrons by the "multipactor effect." The multipactor effect is a phenomenon associated with surfaces whose secondary electron emission coefficient can, within a certain primary electron energy range, be greater than one, and is defined as the buildup of a density modulated electron current due to secondary electron emission in a structure supporting an alternating electric field.

In the specification of Mullett's copending patent application Serial No. 628,381, filed December 14, 1956, an electronic valve is described which has a cathode structure comprising parallel plates adapted to support a radio-frequency electric field normal to their surfaces and to generate electrons from both plates by the multipactor effect, with one of said plates perforated such that an anode placed beyond the perforated plate collects those bunches of electrons which pass through the perforations.

An electronic valve in accordance with the present invention comprises a perforated cylindrical sheet cathode one surface of which has an effective secondary emission coefficient greater than unity, an electrode coaxial with and facing said one surface, an anode coaxial with and facing the other surface and means for setting up in the electrode/cathode space (hereinafter referred to as the multipactor space) both an axial magnetic field and a radial R.F. alternating electric field, the arrangement and applied fields being such that electrons omitted from the emissive surface return towards and either pass through or strike said surface, those passing through being collected by the anode.

The interaction of the electrons with the electric and magnetic fields tends to bunch the electrons for certain values of the magnetic field towards a stable phase with respect to the phase of the alternating electric field and a density modulated electron current builds up in the cyclic repetition of this process. The maximum obtainable circulating electron current is limited by space charge because the field attracting the secondary electrons away from the emissive surface is depressed by the charge of the electron bunch approaching this surface, and in order to reduce this limitation a D.C. voltage is applied across the multipactor space tending to accelerate the electrons away from the emissive surface. The cathode being perforated, some of the bunches of electrons pass through the perforations into the anode/cathode space, herein-after termed the interaction space, across which is applied a D.C. voltage tending to accelerate the electrons away from the perforated surface. The interaction space is so dimensioned that the bunches of electrons traversing it cause an alternating electric field having a period corresponding with, or a multiple of that in the multipactor space to build up as in a class C tuned amplifier.

An amplifying valve according to the present invention comprises means for feeding power into the alternating electric field in the multipactor space, and means for extracting power from the alternating field in the interaction space.

A frequency multiplying amplifier valve according to the present invention may be constructed similarly to said amplifier valve and having the interaction space so dimensioned that the alternating field which builds up in the interaction space is a multiple of that in the multipactor space.

A triggered oscillator valve according to the present invention may be constructed similarly to the amplifier valve but including means for feeding back a fraction of the power generated in the interaction space into the multipactor space, an associated tuned cavity coupled to the interaction space governing the frequency of oscillation and means for feeding sufficient power into the multipactor space to initiate a multipactor build-up of electron current.

A modulated amplifier or oscillator valve according to the present invention may be constructed similarly to the amplifying valve, the output power being modulated by varying the D.C. voltage across the multipactor space and/or the D.C. voltage applied across the interaction space.

In order better to understand the nature of the present invention embodiments thereof will now be described by way of example with reference to the accompanying drawing, of which.

Fig. 1 is a diagrammatic axial section through the multipactor and interaction spaces of one embodiment of the invention.

Fig. 2 is a cross section on line II—II of Fig. 1.

Fig. 3 is a diagram showing the phase notation used in describing the mode of operation and

Fig. 4 is a section similar to Fig. 1 through one embodiment of a triggered oscillator valve according to the invention.

In Figures 1 and 2 the multipactor space M is the annulus between a central electrode 1 and a coaxial perforated cylindrical cathode 2; the interaction space I is the annulus between the cathode 2 and a coaxial anode 3. Solenoidal windings (not shown) around the anode 3 may be the means of providing the necessary axial magnetic field which is substantially uniform over the multipactor space M. The emissive cathode surface providing the secondary electrons is, in this embodiment, the inner surface of the cathode 2. R.F. power enters the multipactor space along an input coaxial line formed by an extension 1a of the electrode 1 and cylindrical extensions 2a of the cathode 2 and is reflected at an end disk 4 which terminates the coaxial line and which is so spaced that a maximum of the R.F. field occurs in the centre of the perforated cathode 2. A negative D.C. voltage is applied to the cathode 2 to provide both a D.C. field across the multipactor space M and an accelerating field across the interaction space I. It is to be understood that these fields may equally well be provided by applying appropriate positive potentials to the centre electrode 1 and outer anode 3. The valve is enclosed by a cylindrical outer wall 3a, of which anode 3 forms a part, and this outer wall 3a is extended in a direction opposite to the extension 1a of the anode 1 to provide, in conjunction with an inner conductor 3b, a coaxial output line from the interaction space I. D.C. open circuits and R.F. short circuits are provided at 6 and 7 and at a convenient position along the cylindrical extension 2a such that the extension 2a, supported on insulating supports, is isolated for the application of the D.C. negative potential. The interaction space I is so dimensioned that the end wall 8 thereof is electrically insulated from the cathode 2.

$$\left(\frac{2n+1}{4} \right)$$

where $n=0, 1, 2, \dots$, wavelengths of the alternating field axially distant from the centre of the perforated cathode.

ode 2. The whole of the space inside the outer wall 3a is evacuated to a low pressure and may be continuously pumped through ports situated at convenient points along the input and/or output lines.

In Figure 3 is shown the phase notation for the electrons in the multipactor space M. An electron leaving the inner surface of the cathode 2 with an initial phase ϕ_1 , with respect to the time when the R.F. field is zero, is accelerated away from this surface and its trajectory is bent by the magnetic field as shown diagrammatically at 9 in Figure 2 so that it arrives back at the cathode surface with a phase ϕ_2 with respect to the R.F. zero field. The initial phase which is stable for cyclic repetition is defined as ϕ_0 and is such that $\phi_2 = 2n + \phi_0$, where $n = 1, 2, 3, \dots$, and the essential conditions for a bunched build-up are that the impact energy is such that the effective secondary emission coefficient of the cathode surface is greater than one and that electrons emitted earlier and later than the stable phase ϕ_0 are bunched towards this stable phase. The effective secondary emission coefficient is to be understood as the ratio of secondary electrons to primary electrons taking into account any losses which occur (e.g. through the perforations). These conditions are satisfied for certain values of the magnetic field strength. In those regions beyond the cathode where it is not desired, and where conditions are favourable for a multipactor build-up of electron current, it must be inhibited by making the surfaces of a material, or of such a geometry, that they have an effective secondary emission coefficient less than one. In addition the spacing of the annular gap can be so reduced that the multipactor build-up cannot occur.

Since the electrons continue to turn under the influence of the magnetic field when passing through the perforations in the cathode 2 and in the interaction space I, the cathode must be made as thin as is mechanically practicable and the spacing between cathode 2 and the anode 3 of the interaction cavity must be small. The gain in tangential velocity by the electrons in traversing the interaction space is dissipated as a heat loss on impact with the anode 3. Reduction of the interaction space gap reduces this loss and increases the efficiency of the D.C. to R.F. conversion, but it also increases the R.F. losses so that a compromise spacing is required.

It is to be understood that in an alternative embodiment the multipactor space may be situated outside the interaction space with the emissive cathode surface on the outside, the electrons passing radially inward through perforations in the cathode into the interaction space.

Since the space charge limited circulating electron current in the multipactor space M is approximately proportional to the D.C. voltage bias across the multipactor space, and the output power for a given current is approximately proportional to the D.C. anode voltage applied across the interaction space I, modulation or pulsing may be applied by varying either or both of these voltages. Pulsing may also be obtained by pulsing the R.F. input. For high power operation forced cooling may be employed. One example of a triggered oscillator according to the invention is shown in Figure 4. The multipactor space M is between the centre electrode 1 and the cathode 2. The interaction space I around the cathode 2 is situated between said cathode 2 and the coaxial outer anode 3. A negative D.C. voltage is applied to the end wall 4 of the cathode extension 2a through rod 10 which passes through a hole in the outer wall 3a and is supported, together with the cathode structure 2, 2a, by the insulating and sealing cap 11. The multipactor space M is so dimensioned that at the operating wavelength the cathode 2 is at a voltage maximum and the end 12 of the cathode extension 2a is electrically one half wavelength distant from the centre of the cathode. The interaction space I is dimensioned such that at the operating wavelength its centre is, axially, at or near the voltage maximum with respect

to an end wall 13 of the interaction space. An end cavity 14 is coupled through an iris 15 (between end wall 13 and cathode extension 2a) to the interaction space and the exact frequency of operation is locked through this coupling to that of the cavity 14. The cavity 14 may be made externally tunable by known means. The axial magnetic field may be provided by solenoidal windings round the outside of the valve.

The extension 1a of the electrode 1 is, in the embodiment shown, the outer conductor of a coaxial line having an inner conductor 16. R.F. power is initially fed through this line into the multipactor space M by any convenient coupling means; a hole coupling 17 is shown schematically in Figure 4. R.F. power is required to be fed through coaxial line 16 to initiate the current build-up since an impact energy in the region of 300 electron volts must be imparted to the electrons in the multipactor region to obtain a secondary emission coefficient greater than one. When the electron current in the multipactor space M builds up, R.F. power is developed in the interaction space as described with reference to Figs. 1-3. This power is fed out along a coaxial output line of which the outer wall 3a constitutes the outer conductor and the extension 1a of the electrode 1 the inner conductor and a fraction of the power, as initially determined by the spacing of the feed gap at 12, is fed back into the multipactor space M. The power absorbed is determined finally by the space charge limitation of the circulating current in the multipactor space. The oscillations may be pulsed and/or modulated by varying the voltage applied to the multipactor cathode 2 and the valve may be evacuated through ports conveniently situated along the output line.

It is to be understood that feed back of power from the output line into the multipactor space and feed of triggering power into the multipactor space may be achieved in a number of known ways through known iris, loop, probe or hole coupling means.

I claim:

40. 1. An R.F. valve comprising a perforated cylindrical sheet cathode, one surface of said cathode having an effective secondary emission coefficient greater than unity, an electrode coaxial with and facing said one surface to form a multipactor space therebetween, an anode coaxial with and facing the other surface of said cathode to form an interaction space therebetween, coaxial extensions of said cathode and said electrode for feeding R.F. power into said multipactor space, coaxial extensions of said cathode and said anode for extracting power from said interaction space, said multipactor and interaction spaces each having an end wall spaced from the center of said perforated cathode whereby said cathode and electrode form with said first mentioned extensions a first shorted coaxial line having a voltage antinode substantially at said center at the operating frequency, said cathode and said anode forming with said second-mentioned extensions a second shorted coaxial line having a voltage antinode substantially at said center at the operating frequency, and means for applying an axial magnetic field within the interaction space.
45. 2. An R.F. valve as claimed in claim 1 wherein said electrode is located coaxially within said cathode.
50. 3. An R.F. valve as claimed in claim 2 wherein means are provided for feeding back a fraction of the power generated in the interaction space into the multipactor space, a cavity resonator is coupled to the interaction space, and means are provided for feeding sufficient R.F. power into the multipactor space from an external source to initiate multipactor build-up.
55. 4. An R.F. valve as claimed in claim 2 wherein said coaxial extensions extend in the same direction, said cathode extension terminating substantially at a voltage antinode at the operating frequency whereby R.F. power is fed back from said second coaxial line to said first coaxial line, a cavity resonator is coupled to the inter-

action space, and means are provided for feeding sufficient R.F. power into the multipactor space from an external source to initiate multipactor build-up.

5. An R.F. valve as claimed in claim 4 wherein said feeding means for initiating multipactor build-up comprises a conductor arranged coaxially within said electrode to form therewith a third shorted coaxial line and a coupling hole in said electrode through which R.F. power from said third line may be fed into the multipactor space.

6. An R.F. amplifying valve comprising a perforated cylindrical sheet cathode, one surface of said cathode having an effective secondary emission coefficient greater than unity, an electrode coaxial with and facing said one surface to form a multipactor space therebetween, an anode coaxial with and facing the other surface of said cathode to form an interaction space therebetween, means for applying an axial magnetic field within the multipactor space, means whereby R.F. power may be

fed into the multipactor space, means whereby R.F. power may be extracted from the interaction space, means for feeding back a fraction of the power generated in the interaction space into the multipactor space, 5 a cavity resonator coupled to the interaction space, and means for feeding sufficient R.F. power to the multipactor space from an external source to initiate multipactor build-up.
